UNITED STATES PATENT OFFICE.

HOLLIS J. SEVIGNY, OF SANFORD, MAINE.

SAFETY TANK CAP OR STOPPER.

Application filed December 11, 1919. Serial No. 344,012.

To all whom it may concern:

Be it known that HOLLIS J. SEVIGNY, a citizen of the United States of America, residing at Sanford, in the county of York and State of Maine, has invented new and useful Improvements in Safety Tank Caps or Stoppers, of which the following is a specification.

The object of the invention is to provide simple and efficient means for preventing the loss or misplacement of removable caps or stoppers such as those used in connection with tanks, radiators or water circulating reservoirs and the like of automobiles and similar vehicles and with reference to which the caps or stoppers must be removed from time to time to permit of refilling or recharging and such caps or stoppers for that reason being subject to more or less frequent loss or misplacement, particularly when the refilling operation is performed in haste or in the dark, and with these objects in view the invention consists in a construction and combination of parts of which a preferred embodiment is shown in the accompanying drawing, wherein:

Figure 1 is a view of the device applied in the operative position to a tank, shown in section, of the type ordinarily employed as a reservoir for gasoline or other fuel.

Figure 2 is a side view of the cap detached.

Figure 3 is a detail section on the plane indicated by the line 3—3 of Figure 1.

The removable cap 10 which is of a type commonly used in connection with tanks 11 of the form shown in the drawing is threaded in the refilling opening of the tank wall or cover and must be displaced to permit of refilling the tank, and in order that after removing the same and releasing it so as to enable the operator to use both hands in manipulating the can or other receptacle or nozzle from which liquid is to be discharged into the tank said cap may be supported within convenient reach for prompt replacement after the completion of the filling operation, there is flexibly connected therewith a limiting element 12 con-

sisting in the construction illustrated of a bar or rod of a length greater than the diameter of the opening in which the cap or stopper is seated and which therefore is adapted to bear terminally against the wall or top of the tank in spanning relation with the said opening while the tank is being filled, the flexible connection as shown consisting of a chain 13.

Preferably the attachment of the chain or other flexible connection to the cap or stopper consists of a clip 14 formed of a metallic or similar plate upturned at one end from the plane of the cap or stopper to form an ear 15 with which the end of the chain is engaged, and perforated at the other end for engagement by a bolt 16 having threaded thereon a nut 17 in contact with a lock washer 18. Also in order that the movement of the limiting element in the tank may not involve the twisting and snarling of the chain or similar flexible connection 13 the attachment of the inner end of said chain with the limiting element is effected by means of a swivel 19 engaged with the bar at or near the center thereof.

Moreover in order that the vibration of the bar or equivalent device serving as a limiting element may not by contact with the sides of the tank cause a rattling sound which might prove annoying to the occupants of a car equipped with the tank, cushioning heads 20 are secured to the extremities of the bar and are preferably constructed of buoyant material such as cork so as to act in the capacity of floats, and to prevent absorption of the liquid, particularly if the device is used in connection with a gasoline tank, these floats may be provided with a liquid excluding and resisting coating of shellac or its equivalent.

The cushioning heads 20, being of buoyant material as above described, serve to support the limiting device at the top of the liquid contents. Thus when the cap 10 is removed, the flexible connection between the limiting device and the cap may be used as a gauge to determine the level of the liquid contents, the extent of the exposed portion

of the chain or flexible connection, when the weight of the limiting device becomes apparent, determining the level of the contents.

What is claimed is:—

5. A limiting device for tank caps or stoppers consisting of a limiting element longitudinally insertable through the opening fitted with said cap but of a length greater than the diameter of said opening, said ele-

ment being provided with enlarged buoyant heads of cushioning material, and a flexible element terminally connected respectively with the cap and with an intermediate point on said limiting element.

In testimony whereof he affixes his signature.

HOLLIS J. SEVIGNY.
